UNITED STATES PATENT OFFICE.

PATRICK FRANCIS DENNING, OF CLEVELAND, OHIO.

DESIGN FOR AN INDIVIDUAL ARTICLE-HOLDER.

55,756.

Specification for Design. Patented July 13, 1920.

Application filed August 26, 1919. Serial No. 320,076. Term of patent 14 years.

To all whom it may concern:

Be it known that I, PATRICK F. DENNING, a citizen of the United States, residing at Cleveland, in the county of Cuyahoga and State of Ohio, have invented a new, original, and ornamental Design for an Individual Article-Holder, of which the following is a specification.

Referring to the drawing:—

Figure 1 is a perspective view of an individual article holder showing my new design;

Fig. 2 is a side elevation of the device; and,

Fig. 3 is a front elevation of the same.

I claim;—

The ornamental design for an individual article holder substantially as shown.

In testimony, that I claim the foregoing as my own, I have hereto affixed my signature in the presence of two witnesses.

PATRICK FRANCIS DENNING.
